UNITED STATES PATENT OFFICE.

NATHAN RUBENSTEIN, OF NEW YORK, N. Y.

BED-SPRING.

SPECIFICATION forming part of Letters Patent No. 737,278, dated August 25, 1903.

Application filed December 2, 1902. Serial No. 133,622. (No model.)

To all whom it may concern:

Be it known that I, NATHAN RUBENSTEIN, a citizen of the United States, and a resident of New York, borough of Manhattan, in the county of New York and State of New York, have made and invented certain new and useful Improvements in Bed-Springs, of which the following is a specification.

My invention relates to an improvement in bed-springs, the object being to so construct a device of this character that the tension of the several springs may be easily and readily regulated, and whereby any one or more of the several parts constituting the complete spring may be removed and replaced, and also whereby the same may be adjusted to fit beds of different or varied widths.

With these and other ends in view the invention consists in certain novel features of construction and combinations of parts, as will be hereinafter fully described, and pointed out in the claims.

In the accompanying drawings, Figure 1 is a plan view of a part of a bed-frame having a bed-spring constructed in accordance with my invention resting thereon. Fig. 2 is a sectional view taken on the line 2 2 of Fig. 1. Fig. 3 is a sectional view taken on the line 3 3 of Fig. 2, and Fig. 4 is a detached view of one of the supporting-arms.

Referring to the drawings, 5 represents a part of a bed-frame constructed in any suitable way, and 6 several sections of which the bed-spring consists. As the spring is made up of any suitable manner of these sections, all constructed alike, the description of one will suffice for the others. Extending crosswise of the bed-frame and resting thereon is an adjustable support, consisting of a rod 7, the ends 8 of which are threaded into the sleeves 9, formed on the lower end of the vertical arms 10, the upper ends 11 of said arms 10 being bent over to rest upon the bed-frame 5, this construction and arrangement of parts allowing of the adjustment of the arms 10 on the rod 7 to adapt the spring to any width of bed-frame. This adjustable support carries the spring proper, consisting of the strap or band 12, preferably made of thin sheet-steel, the opposite edges of which, near its ends, are cut or notched,

as shown at 13, for the reception of the loops 14, each secured to one end of the coiled springs 15, the opposite ends of these springs being provided with the loops 16, fitting in the grooves 17, formed in the bent ends 11 of the arms 10, a spring 18 being also secured between the strap 12 and bar 7, if desired.

From the foregoing it will be understood that the tension of the springs forming each section may be increased or decreased by properly adjusting the loops 14 in the several notches 13, that the springs 15 may be easily and readily detached and others substituted therefor, and also that by reason of the fact that the several sections are independent of each other the tension of the springs of one section may be changed or altered without in any way affecting the springs of the remaining sections.

Having fully described my invention, what I claim as new, and desire to secure by Letters Patent, is—

1. A bed-spring consisting of several sections, each section consisting of a supporting-bar having its ends adjustably secured in supporting-arms adapted to rest on the bed-frame, a strap-spring, coiled springs adjustably secured to the ends of said strap-spring and removably secured to said supporting-arms, and a spring located between and having its ends secured to said strap-spring and supporting-bar, substantially as described.

2. A bed-spring formed with several sections, each section consisting of a supporting-bar 7 having its ends threaded into the vertical arms 10 adapted to rest upon the bed-frame, and provided with grooves 17, a strap-spring 12 having its ends notched, springs 15, the ends of which fit in said notches in said strap-spring and into said grooves 17 formed in the supporting-arms, and a spring 18 located between and secured to said strap-spring 12 and supporting-bar 7, substantially as described.

Signed at New York, borough of Manhattan, in the county of New York and State of New York, this 29th day of November, A. D. 1902.

NATHAN RUBENSTEIN.
